UNITED STATES PATENT OFFICE.

OREN E. WYLIE, OF WASHINGTON, KANSAS.

CURTAIN-BRACKET.

1,275,821.

Specification of Letters Patent. Patented Aug. 13, 1918.

Application filed June 1, 1917, Serial No. 172,247. Renewed June 22, 1918. Serial No. 241,438.

To all whom it may concern:

Be it known that I, OREN E. WYLIE, a citizen of the United States, residing at Washington, in the county of Washington and State of Kansas, have invented certain useful Improvements in Curtain-Brackets, of which the following is a specification, reference being had therein to the accompanying drawing.

- 10 The present invention has reference generally to improvements in that class of inventions known as curtains, shades and screens and more particularly relates to a curtain bracket.
- 15 As the primary aim and object, this invention resides in the provision of novel means for removably clamping the bracket in engagement with the upper ends of a window casing.
- 20 More particularly, the present invention embraces the provision of coöperative relatively adjustable angle clamps on the bracket and arranged to engage the inner and outer corners of the window casing so as to effectively support the bracket.

- The invention as a further improvement consists in the provision of novel means for adjusting the removable angle clamps forming a part of the bracket.
- 30 Among the other aims and objects of the present invention may be recited the provision of a device of the character mentioned with a view to compactness, and in which the number of parts are few, the construction simple, the cost of production low and the efficiency high.

- Other improvements and novel details in the construction and arrangement of the various parts of the apparatus will be brought out more in detail in the description to follow, which for a clear understanding of the invention should be considered in connection with the accompanying drawings forming a part hereof, wherein is disclosed for the purpose of illustration a convenient and satisfactory embodiment of the invention. It is to be noted in this connection that various minor changes in the construction and arrangement of parts may be made without departing from the spirit of the invention or the principle of operation of the various parts.

The invention is clearly illustrated in the accompanying drawings, in which—

- 55 Figure 1 is a front elevation of the invention in position on a window casing.

Fig. 2 is an enlarged transverse section taken on line 2—2 of Fig. 1.

Fig. 3 is a perspective detail of one of the brackets.

Similar reference characters are employed in all of the above described views, to indicate corresponding parts.

Referring now, more particularly, to the accompanying drawings there is illustrated a window casing including side pieces 1 and an upper cross piece 2 connected at the respective ends by means of caps 3. Removably mounted at the upper corners of the casing about the caps are improved curtain rod supporting brackets indicated in their entirety by the numeral 4.

In the present instance each of these brackets consists of a body 5 which is disposed diagonally across the outer face of one of the caps and extending in a direction from the inner corner to the outer corner thereof, the outer end being bent at right angles and twisted so as to be arranged diagonally of the plane of the body, being secured to the inner surface of a stationary angle clamp 6 by means of a suitable fastening device 7. As indicated in the drawings the stationary angle clamp is engageable with the outer corner of one of the caps 3 so that the opposite end of the body projects beyond the inner corner of the casing while an inwardly extending flange 8 is formed thereon.

Coöperating with the stationary angle clamp 6 is a movable angle clamp 9 which is arranged so that the outer surface thereof will engage the inner corner of the window casing.

As intimated improved means have been provided for adjusting the movable angle clamp. In reducing this feature of the invention to practice, a screw 10 is adjustably mounted in the threaded aperture 11 in the flange 8 while a ball 12 is formed on the inner end of the screw and is universally mounted in a socket 13 carried by the inner surface of the movable angle clamp 9 at its point of distortion 14. A wing head 15 is formed on the outer end of the screw and facilitates manual adjustment thereof to consequently move the angle clamps 6 and 9 respectively into engagement with the outer and inner corners of the casing as indicated in Fig. 1.

In order to provide improved means on the bodies 5 of each of the brackets 4 for

supporting a curtain rod or the like angle supports 16 are employed, the securing portions 17 being rigidly connected to the bodies intermediate the ends thereof by suitable fastening devices 18, so as to maintain the securing portions approximately horizontally of the window casing. The supporting portions 19 extend at right angles thereto and are provided with rod receiving openings 20. As will be appreciated the portions 19 are arranged approximately vertically of the window casing when the brackets are in the position as indicated in Fig. 1.

15 It is thought in view of the foregoing description that a further detailed description of the operation of the invention is entirely unnecessary. Likewise it is believed that the advantages of the invention will be readily apparent.

20 As many changes could be made in the above construction and many apparently widely different embodiments of this invention could be made without departing from the scope thereof, and it is intended that all matter contained in the above description or shown in the accompanying drawings shall be interpreted as illustrative and not in a limited sense. It is also to be understood that the language used in the following 25 claim is intended to cover all the generic and specific features of the invention herein de-

scribed and all statements of the scope of the invention which as a matter of language might be said to fall therebetween. 35

Having thus fully described this invention, what is claimed as new and desired to be secured by Letters-Patent, is:

In a curtain bracket comprising a body formed from a piece of strap metal adapted 40 to be disposed diagonally across the outer face of one cap of a window casing and having the outer portion bent at right angles and twisted so as to be arranged diagonally of the plane of the body, a stationary angle 45 clamp carried by the outer bent portion of the body and adapted for engagement with the outer corner of the cap of a window casing, an inwardly extending flange formed on the inner end of the body and having a 50 threaded opening therein, a movable angle clamp adapted for engagement in the inner corner of the window casing, a socket carried by the inner surface of the movable angle clamp adjacent the point of distortion 55 thereof, a screw adjustably mounted in the opening in the flange and universally connected in the flange in the socket, a wing head formed on the screw for facilitating adjustment, and a curtain rod support carried by the outer face of the body. 60

In testimony whereof I affix my signature.

OREN E. WYLIE.
